CUE RACK

Filed May 5, 1921

FIG. 1.

FIG. 2.

FIG. 3.

Inventor:
By: C. HINE
W. M. DELAHAY.

UNITED STATES PATENT OFFICE.

CICERO HINE, OF CHICAGO, ILLINOIS, ASSIGNOR TO THE BRUNSWICK-BALKE-COLL
LENDER COMPANY, A CORPORATION OF DELAWARE.

CUE RACK.

Application filed May 5, 1921. Serial No. 466,961.

To all whom it may concern:

Be it known that I, CICERO HINE, a citizen of the United States, residing at Chicago, in the county of Cook and State of Illinois, 5 have invented certain new and useful Improvements in Cue Racks, of which the following is a specification.

This invention relates to racks for holding cues used in playing billiards and pocket 10 billiards and its object is to provide a simple and efficient device which will permit the insertion and removal of the cues without injury thereto and which will hold the cues securely in an upright position.

15 Other objects and advantages of my invention will be apparent as it is more fully described hereafter with reference to the accompanying drawing which illustrates a selected embodiment of the invention and in 20 which

Fig. 1 is a front elevation of a cue rack embodying the invention.

Fig. 2 is a top plan view.

25 Fig. 3 is a horizontal sectional view on the line 3-3 of Fig. 1.

Referring to the drawings, a frame 4 of suitable form is intended to be secured in upright position to a wall or other support, and it is provided with a base 5 having 30 sockets 6 to receive the butt ends of the cues 7. A transverse rack bar 8 having a plurality of recesses 9 registering with the sockets 6 is secured to the side members 4'-4' of the frame about midway between 35 the base 5 and the top plate 10 of the frame. A retaining or keeper bar 11 is mounted on the top plate and spaced in front thereof sufficiently to form an elongated, narrow, transverse space 12 to receive the cues as 40 shown in Fig. 1. The sockets, recesses and retaining bar 11 are located with reference to each other so that when the cues are in place with their butt ends seated in the sockets the cues will rest snugly in the recesses of the rack or guide bar 8 and their upper ends will be held snugly against the retaining bar 11. I consider this a desirable construction because the cues will then be held upright with their butt ends against 45 the front walls of the sockets, and their upper ends against the retaining bar by the rack or guide bar engaging the cues substantially midway between their ends and located on the side of the cues opposite to 50 that of said walls and retaining bar. It

will be noted, of course, that the cues rest in the recesses 9 and are therefore spaced apart and are held upright against lateral movement while the position of the guide or rack bar on one side of the cues in cooperation 60 with the retaining bar and the front walls of the sockets on the other side of the cues will maintain the cues in upright position against forward or backward movement. Not only do these means hold the cues upright but they tend to prevent the cues from warping. For the foregoing reasons I prefer this stated relationship of the sockets, recesses and retaining bar but if this relationship is not maintained so carefully as I have 65 suggested the invention will still present many advantages over cue racks heretofore used, so far as I am aware, by reason of its simplicity and the ease with which cues may be inserted and removed without injury 70 thereto. The elongated slot or space between the retaining bar and the top plate, permits the insertion and removal of the cues without injury to the tips and for this purpose the space may be of considerable 75 width since only the retaining bar is employed for holding the cues upright. The back wall of the sockets might also be dispensed with because it is the front wall which cooperates with the rack and guide 80 bar and the retaining bar to hold the cues upright but this is a detail which I do not regard of any importance in the commercial use of the invention since it will probably be more convenient to make the sockets circular 85 90 as indicated than otherwise.

I am aware that my invention may be embodied in other forms than that herein disclosed which, as before stated, is a selected embodiment of a simple form of 95 the invention and I therefore reserve the right to make all such changes as fairly fall within the scope of the following claims.

I claim:

1. A cue rack comprising a frame having 100 a base to receive and support the cues and means rigidly secured to the frame engaging the cues on one side at the top and bottom thereof and on the opposite side between the top and bottom thereof for holding the 105 cues in upright position.

2. A cue rack comprising a frame having 110 a base to receive and support the cues, means on the frame engaging the cues at the front and at the top and bottom thereof, and

means on the frame engaging the cues at the back and between the top and bottom thereof for holding the cues in upright position.

5. 3. A cue rack comprising a frame having a base to receive and support the cues, means on the frame engaging the cues at the front and at the top and bottom thereof, and means on the frame engaging the cues at 10 the back thereof and spacing the cues from each other between the top and bottom thereof.

4. A cue rack comprising a frame having a base provided with sockets to receive the 15 butt ends of the cues, a retaining bar to engage the cues at the front adjacent the upper ends thereof, and a rack bar engaging the cues at the back thereof between their ends and spacing them apart.

20. 5. A cue rack comprising a frame having a base provided with sockets to receive the butt ends of the cues, a rack bar engaging the cues between their ends to prevent them from moving rearward and for spacing 25 them apart, and a retaining bar engaging

the cues adjacent the top thereof to prevent forward movement of the cues.

6. A cue rack comprising a frame having a base provided with sockets to receive the butt ends of the cues and an elongated retaining space at the top of the frame to receive the upper ends of the cues, and a rack bar on the frame between the bottom and top thereof and rigid with respect to the base for engaging the cues between their 35 ends at the back thereof and for spacing the cues apart.

7. A cue rack comprising a frame having a base provided with sockets to receive the butt ends of the cues, a top plate, a retainer 40 bar spaced from the top plate to provide an elongated space for receiving the upper ends of the cues and to engage the cues at the front thereof, and a rack bar on the frame between the bottom and top thereof 45 provided with recesses to receive the cues to prevent rearward movement thereof and to space the cues apart.

CICERO HINE.
